UNITED STATES PATENT OFFICE

STANLEY W. HAYES, OF RICHMOND, INDIANA, ASSIGNOR TO HAYES TRACK APPLIANCE COMPANY, OF RICHMOND, INDIANA, A CORPORATION OF INDIANA

BUMPER POST

Application filed August 20, 1931. Serial No. 558,283.

The invention relates to improvements in bumper posts of the type in which a bumper head located between the rails is supported from the road bed by compression and tension means and, in the post illustrated, by divergent compression members and by divergent tension members secured to the road bed, the term "road bed" being here used broadly to indicate the ballast, ties, rails, or any of them. The object of the invention is to provide an easily constructed and assembled, relatively light and low cost bumper post of the requisite strength to sustain the severe shocks to which such structures are subjected and applicable without change to rails of various heights. To that end it includes improvements in the form or structure, or in both the form and structure, of the principal elements of the post, in the mode of connecting them to each other and to the road bed, and in their general combination and arrangement, as explained in the specification and more particularly pointed out in the claims.

Referring to the drawings, Fig. 1 is a perspective view of the bumper post in its preferred form.

Fig. 2 is a side elevation on a larger scale, parts being broken away and the right hand tension connection to the road bed being in section on the line II—II, Fig. 4.

Fig. 3 is a plan.

Fig. 4 is a vertical section on a larger scale on the line IV—IV, Fig. 3, transversely through the right hand tension connection to the roadbed.

Fig. 5 is a detail perspective, partly in section, of the right hand tension track fixture plate, parts being broken away and indicated in phantom lines.

Fig. 6 is a sectional plan of said tension connection, parts being broken away to show hidden details.

Fig. 7 is a cross section through the rail showing a left hand tension connection modified for use on a girder trestle.

Fig. 8 is a section through the cross beam showing another modified (right hand) rail tension connection.

Fig. 9 is a detail perspective view on a

larger scale showing elements of the compression track fixture and the end of the left hand compression member in separated relation prior to their welding together.

Fig. 10 is a detail perspective view of the left hand compression member and compression track fixture, its relation to the rail being indicated by the phantom showing of the latter.

Fig. 11 is a perspective from another point of view of the structure of Fig. 10.

Fig. 12 is a vertical cross section through the left rail in rear of the compression track fixture.

Fig. 13 is a true view or plan in the plane of the upper side of the bumper head.

Fig. 14 is a rear elevation of the bumper head, parts being broken away to show the interior construction.

Fig. 15 is a vertical section through the bumper head, etc. on the line XIV—XIV, Fig. 14.

Fig. 16 is a detail perspective, partly in section, of the left bumper head tension connection.

Fig. 17 is a plan, partly in section and on a reduced scale, of a bumper head, modified for passenger cars.

Fig. 18 is a vertical section on the line XVIII—XVIII, Fig. 17, and

Fig. 19 is a section on the line XIX—XIX, Fig. 17.

In the structure above taken for exemplification of the invention, castings are eliminated and the bumper head and track fixtures built up from rolled steel sections by welding (preferably electric welding) thus saving weight, and reducing the number of parts, as compared with usual bumper post practice, and increasing facility of handling and setting up by welding each compression member to its compression track fixture and by welding each tension member to its tension track fixture, so that exclusive of fastening bolts and filler pieces, the post has only nine separate parts, namely two compression and track fixture members, the tie-rod connecting them, two tension and track fixture members, two U-bolts (where used), the tension cross beam and the bumper head, which is support-

ed between the tracks, in the usual slightly off center position, by the other parts referred to, as shown in Figs. 1, 2 and 3. This reduced number of parts materially simplifies the process and labor of erection.

5 The term "bumper head," without more, is used throughout the specification and claims in a broad sense to indicate generally, and regardless of the particular construction, those 10 parts of the post to which the stress of impact is delivered. In the structure illustrated, however, the details of which are now to be described but without limitation thereto except where included in particular claims, 15 instead of the customary heavy casting, the bumper head is a light, but strong, box-structure fabricated by welding together rolled plate-steel members as best shown in Figs. 13, 14 and 15. In these figures 1 indicates the 20 bumper face plate, 2 and 3 side plates both cornering on the back of the bumper face plate 1 at the outer front edge of each and welded thereto, 4 and 5 inner top and bottom end abutment plates cornering on the back of 25 the face plate at the lower front edge of each and welded thereto between the side plates, said plates extending downward and rearward in parallel planes, 6 a vertical brace and spacer plate having its front edge in the 30 plane of the rear of the face plate and welded thereto and its top and bottom edges respectively in the planes of the plates 4 and 5 and welded thereto, and 7 and 8 top and bottom cover plates cornering on and welded 35 to the rear of the face plate at the lower front edge of each and welded to both of the side plates. The plates 7 and 8 may extend beyond the side plates and both are provided with bolt holes 9 each aligned axially with 40 one of the bolt holes in the other plate. The top cover plate 7 may have a groove 10 in each side edge for the reception of a tension member, as will be hereinafter explained. All the plates are brace plates, since they 45 strengthen and brace the structure.

The shape and relation of the various plate members or plate pieces will be apparent from the drawings and particularly from Figs. 13, 50 14 and 15. They are square-sheared and welded in cornerwise relation to the back of the face plate which avoids the necessity of finishing their front edges on an angle or beveling to fit the face plate and makes it possible to readily weld them at any desired angle. Welding fills in the crevice, thus producing ample bearing and attachment of one section to the other. This arrangement not 55 only promotes strength and lightness but makes it possible to vary the shape of the head at will to suit particular compression members or other special conditions. The 60 readiness of adaptability thus obtained is indicated by the modified construction of the head shown in Figs. 17, 18 and 19, wherein 65 the head shown in the other figures and which

is adapted to freight cars, is extended forward to give additional clearance to the air hose and steam connections as used in passenger cars and is provided with means for returning the coupler bar to center, which 70 is desirable, since the ends of passenger cars, as is well-known, have a much longer swing than the ends of freight cars. In the three figures referred to, spacer brace plates 11, 75 shown as identical horizontal plates, with curved front edges, equally spaced vertically are welded to the front of the face plate 1 and to the rear of the horizontally concave striker plate 12. Side cover plates 13, 14 may be welded to the front of the face plate 1, 80 the rear of the plate 12, and to the adjacent ends of the space plates. The various plates used in the bumper head and its extension may be of any appropriate thickness, but I have found that face plates of $1\frac{1}{4}$ " thickness and other plates $\frac{1}{2}$ " thick serve the purpose. 85

The bumper head as thus formed provides a box opening downward at the rear and of suitable dimensions to receive the upper 90 front ends of both the compression members 15 which are preferably H beams, since beams of this cross section are much stiffer than channels or members of other cross section. As indicated in Fig. 13, the forward ends 95 of the H-beams 15 abut respectively on the adjacent rear edges of the plates 4, 5. The flanges of the H-beams are in contact at the top with the underside of the cover plate 7 and at the bottom with the upper side of the 100 cover plate 8; their outer edges are in contact with the inner sides of the side plates 2, 3 and the inner front corners of the flanges of the left hand H-beam are in contact with the inner edges of the right hand H-beam, so that the said ends of the H-beams occupy the 105 said space in the bumper head across the head and the parts are maintained in right relation and the structure well braced. Separate housing of the ends of the H-beams is unnecessary, the arrangement described being preferred. While H-beams are for reasons stated particularly desirable as compression members, they do not readily lend themselves to such use owing to the difficulty of associating them in proper thrust contact with the bumper head and particularly with the rails and road bed. The way in which their 110 relation to the bumper head has been taken care of has just been described, the other 115 part of the problem has been solved in the manner now to be stated. 120

Referring particularly to Figs. 9 to 12, the compression track fixtures which are substantially the same but reversed are built up out 125 of plate or plate-like elements, as indicated in Fig. 9, which illustrates the left hand compression fixture showing separated the elements considered most desirable along with the end of the adjacent H-beam, which is 130

to be welded to the track fixture to form a composite compression unit. In the illustrated embodiment of the invention, these elements are the parts numbered 16, 17 and 18 and they and the H-beam are welded together in any convenient order. Of these elements, 16 is the rail-engaging plate, which has a base 19 adapted to seat on the flange at the inside of the rail, preferably by pads 20 welded thereto and having their bottoms inclined to suit the incline of the top of the rail flange, and an upright rail attachment flange 21 having bolt holes 22 and preferably having spacer pads 23 welded thereto and through which said holes extend. Part 17, an angle having end abutment 24 and leg 25, is secured to the plate 16, preferably by welding its side edge 26 to the inside face of the upright flange 21 and having its lower rear edge 26' cornering on and welded to the base 19. The abutments 24 are supported sufficiently inward of the rail to avoid need of any mitering or special fitting of the H-beam in order to produce a proper bearing of the one upon the other; square-sawed H-beams are thus made available. The upstanding brace plate 18 which may serve also as a tie-rod-anchoring plate is welded both to the base 19 and to both legs of the angle 17 into which it fits. It is located, in the construction shown, in a vertical plane parallel to the flange 21 and spaced therefrom. The angle 17 and in particular the end abutment 24 is thus firmly supported in a plane at right angles to the axis of the H-beam whose lower end is in the same plane as the abutment 24, and welded thereto. A flange side of the H-beam is preferably uppermost, the flanges at its underside and the leg 25 of angle 17 being in line and the web of the H-beam registering with the front end of the brace plate 18. The H-beams are thus sustained very strongly against endwise thrust delivered on face plate impact. The brace plates 18 of the respective compression fixtures, as here shown, serve also to anchor the ends of the tie bar 27, each having an upwardly facing notch 28 and a lug 29 welded adjacent the notch in position to permit the tie bar to be laid therein, before the compression track fixtures are set in their final positions, in which the lugs 29 then overlie the heads 30 and thus lock the bar in place, as in my Patent No. 1,705,479, granted March 19, 1929. A bolt bar or clamp plate 31 having bolt holes spaced correspondingly to those in the flange 21 of the rail-engaging member is desirably used as indicated in the drawings in place of individual washers. Bolts 32 passing through the holes in clamp bar 31, the web of the rail and the flange 21 secure the composite compression member and track fixture in place. The particular composite compression member above described is of course subject to modification in the shape and arrange-

ment of its individual welded-together plates according to the preference of the maker or the contour of the beam part. It is convenient to speak of the "compression track fixtures" as if they were distinct from the "compression members", but, in the structure illustrated, they are actually extensions of the respective compression members being integral therewith in the finished structure.

The tension members are shown as bars 33 of circular section having welded thereto, at one end, means for fastening the bar to the head and at the other, means for fastening the bar to the road bed, such means being in the nature of integral side extensions as will appear in the detailed description, in which, for convenience, they are designated by separate names. As shown in Figs. 3, 13, 15 and 16, the upper end of each bar 33 passes through a hole 33a in an off-setting block 34 to whose faces the walls of the hole are normal and to which the bar is welded. The block 34, when the post is assembled, seats on top of the cover plate 7 which lies in a plane inclined to the vertical and to the horizontal, and the block extends inwardly and rearward, and the bar outward and forward. The axes of the bar and hole are thus angularly related, as indicated in Fig. 16, and the bar 33 touches only the inner side of the top edge of the hole and the outer side of the bottom edge of the hole leaving space in the hole for the fused steel or welding material above the bar toward the outer side and below the bar toward the inner side. This makes an exceptionally secure attachment. Each of these blocks is also provided with a hole adapted to register with a pair of the holes 9 in the top and bottom cover plates and with corresponding holes in the upper or housed ends of the compression members. Bolts 35 pass through each of these sets of registering holes and are secured in place by nuts 36, the construction being substantially the same at each side of the head.

The preferred tension connection to the road-bed, substantially duplicated, in reverse, adjacent each rail, is shown in Figs. 1 to 6 inclusive, wherein each tension bar 33 is shown as passing through a hole 33b in the horizontal plate portion 37 of the tension track fixture adjacent the upturned rail attachment flange 38 and welded to the track fixture at both sides of it.

As will appear from Fig. 5, the hole 33b is formed of about the size of tension bar and then reamed or dressed off to accommodate the angle of the bar and the resulting crevices are filled in with fused steel in the welding of the parts together. The bar is thus welded on both faces of the plate. The tension structure is designed to transmit the strain to a heavy cross beam 39, extending between the ties, across the track and seating

under the respective rails as in my pending application, Ser. No. 390,417, filed September 5, 1929, wherein specifically different structure having common characteristics is shown and broadly claimed. The plate 37 has welded thereto a spacer pad 40, which seats on the top of the cross beam 39, thus locating the plate 37 in a horizontal plane. In the construction illustrated in the said figures, 10 the tension structure includes means for receiving and surrounding the cross beam. This is a **U**-bolt 41 whose closed end having welded therein a filler half disc 42 seats on the underside of the cross beam, the bolt being provided with nuts 43 and having its legs at the ends of the spacer pad 40. The rail-attachment flange 38 of the tension track fixture has welded thereto pads 44 which seat on the inside of the rail web. Said flange, pads 20 and web are drilled to provide holes for attaching bolts 45, which pass also through correspondingly located bolt holes in clamp bars 46, similar to the clamp bar shown in Fig. 9 but shorter and having only two bolt 25 holes and are secured by nuts 47. Lugs 48 welded to the top flange of the cross beam 39 near each end of the beam serve as abutments for the inner edge of the respective plates 37 to prevent the plates from being 30 drawn toward each other on bumper impact. It will be apparent that the composite tension and track fixture member as well as the composite compression and track fixture member can be handled as a unit. The tension track fixtures are located directly opposite to each other in the track and serve to correctly locate and anchor the tension cross beam and to transmit stress of bumper impact thereto and also to the respective rails 40 to which the plate members 37 are attached. The tension bars are welded to the track fixture plate at a point between that at which the tension structure embraces the cross beam (**U**-bolt) and that at which the tension structure 45 is secured to the rail (bolts 45), so that the pull of the tension member distributes part direct to the rail web and part to the beam 39 and rail base.

A slight modification of the tension connection to the rail and road bed is illustrated 50 in Fig. 7, which represents this connection as applied to a girder trestle, such as is used for coal pockets and wherein an I-beam 49 underlies each rail. Here, also, the tension bar 33 passes through and is welded to the base plate 37 of the tension track fixture, which has the pad 40 and the rail attachment flange 38 and is secured to the rail web in the manner described in connection with Figs. 1 55 to 6. It will be observed, however, that plate 37 is extended further inward toward the center of the track to clear the flange of the I-beam and that the lug 50 welded to the top 60 of the cross beam 39 is extended under the adjacent flange of the I-beam and has its up-

per surface inclined to correspond with the under surface of the I-beam flange. It will be seen also that the lug 50 extends further above the upper side of the cross beam 39, as it must, in order to oppose the inner edge of 70 the plate 37. The **U**-bolt is also necessarily longer and is located just beyond the pad 40.

Another modification of the tension connection to the track is shown in Fig. 8, where-in the closed end of the **U** constituted by the 75 **U**-bolt is omitted and upright bars or legs 51 are welded to the front and back of the cross beam 39, filler blocks 52 of substantial width being welded to the respective channels and to said legs. The rest of the structure is as above 80 described in connection with the form illustrated by Figs. 1 to 6. No attempt has been made to exhaust the possibilities in designing modified forms of the tension connection, and it is to be understood that, except as may 85 be specified in particular claims, the invention is not limited to the details shown. The modified construction illustrated in Fig. 8 has the advantage of requiring less excavation and it or some other arrangement, preferably 90 of welded parts, which does not extend below the bottom of the tension cross beam but which secures it with requisite strength to the rest of the tension structure may be employed.

This post without alteration fits any rail 95 from 5" to 7" high. By modifying it slightly, it can be constructed to suit lower or higher rails. The parts are so light and so readily handled that the simple operations incident to setting up the post can all be performed by 100 one man.

I claim:

1. A bumper post having a bumper head between the rails, compression members secured thereto and extending downward, outward and rearward therefrom and having welded thereto compression track fixtures built up by welding together elements composing them, and secured to the respective rails at points opposite each other in the track, and tension members extending downward, outward and forward from the bumper head and secured to the road bed in advance of the bumper head to transmit thrust of impact therefrom. 110

2. A bumper post having a bumper head between the rails, compression members secured thereto and extending downward, outward and rearward therefrom, compression track fixtures secured to the road bed at points 115 opposite each other in the track and each having an end abutment member supported off the rail in a plane at right angles to the axis of the adjacent compression member and to which said compression member is welded, and tension connections from the bumper head to points in the road bed in advance of the head. 120

3. A bumper post having a bumper head 125 between the rails, compression members se-

- cured thereto and extending downward, outward and rearward therefrom, compression track fixtures secured to the road bed at points opposite each other in the track, each compression member being welded to the adjacent track fixture, and tension connections from the bumper head to the road bed in advance of the head. 5 70
4. A bumper post having a bumper head between the rails, strut means secured thereto and to the road bed for transmitting thrust of impact from the bumper head, and divergent tension members secured to the bumper head and having welded thereto tension track fixtures secured to the respective rails at points opposite each other in the track. 10 75
5. A bumper post having a bumper head built up of plate elements welded together into a box structure presenting at its rear a common downwardly and rearwardly opening recess closed at the top bottom and sides and having end abutments in angularly related transverse planes, compression members having their upper ends in said common recess, secured to the head, abutting respectively against said end abutments and extending downward, outward and rearward therefrom to the road bed to transmit thrust of impact thereto, and tension connections from the bumper head to the road bed. 15 80
6. A bumper post having a bumper head built up of plate elements by welding, compression members having their upper ends extending into the interior of the bumper head and abutting endwise thereon, secured thereto and diverging outward, rearward and downward therefrom, and tension members secured to the bumper head and diverging outward, forward and downward therefrom, both said compression members and said tension members being welded to track fixtures having elements welded thereto and secured to the respective rails at points opposite each other in the track to distribute stress of impact to the road bed. 20 85
7. A bumper post having a bumper head presenting a common rearwardly and downwardly opening recess, a pair of H beams having their upper ends together fitting and occupying said recess, secured to the head structure, abutting endwise thereon and diverging outward, rearward and downward therefrom, and compression track fixtures secured to the respective rails at points opposite to each other in the track and each supporting in a plane at right angles to the axis of the H beam a member against which the end of the H beam abuts and to which it is welded. 25 90
8. A bumper post having a bumper head presenting a common rearwardly and downwardly opening recess, a pair of H beams having their upper ends in sidewise contact with each other and together fitting and occupying said recess, abutting endwise on the 30 95
- head structure and diverging outward, rearward and downward therefrom, compression track fixtures secured to the respective rails at points opposite to each other in the track and having a part against which the lower end of the H beam abuts and to which it is secured, and tension structure connecting the bumper head to the road bed to transmit stress of impact thereto. 35 100
9. A bumper post having a bumper head presenting a common recess, compression members having their upper ends received therein and abutting respectively on shoulder faces angularly related to each other and forming part of the head structure, said compression members being adapted to deliver thrust of impact to the road bed, and tension members connecting the head to the road bed in advance of the head. 40 105
10. A bumper post comprising a bumper head supported between the rails, compression members diverging outward, rearward and downward therefrom and having their lower ends abutted on and welded to anchoring track fixture means bolted to the respective rails at points opposite each other in the track, and tension members having their upper ends secured to the bumper head and extending downward, outward and forward to anchoring track fixture structures located opposite each other in the track adjacent the respective rails and to which the lower ends of the tension members are welded. 45 110
11. A bumper post comprising a bumper head supported between the rails, compression members diverging outward, rearward and downward therefrom and having their lower ends secured to the respective rails at points opposite each other in the track, and tension members having their upper ends welded to bumper head structure and extending downward, outward and forward from the weld to anchoring track fixture structures located opposite each other in the track adjacent the respective rails and to which the lower ends of the tension members are welded. 50 115
12. In a bumper post, a bumper head having front and side plates, top and bottom cover plates, and top and bottom inner shoulder plates welded into a unitary structure and in which the front plate spans the space between the side plates and the space between the cover plates and in which all the other plates are angularly related to the front plate, said side plates and cover plates extending rearward and downward beyond the shoulder plates to provide space for receiving the upper ends of compression members. 55 120
13. A bumper head for a bumper post fabricated by welding square-sheared rolled steel plates in a hollow structure, one of said plates being a bumper plate and others of said plates cornering on and welded to the 60 125
- 65 130

back of the bumper plate along the line of corner contact.

14. In a bumper post, a bumper head between the rails having a substantially upper right plate, a set of square-sheared plates located in planes at angles thereto, cornering on and welded to the back of said plate and related to adapt the head to receive the upper ends of divergent compression members, and having common means for securing compression members and tension members to the bumper head.

15. In a bumper post, a bumper head having a bumper plate designed for location in a substantially vertical plane transverse of the track, top and bottom cover plates and top and bottom inner square-sheared plates cornering on the rear face of the bumper plate at their upper ends and welded thereto, and square-sheared side plates adjacent the cover plates cornering on and welded to the rear face of the bumper plate, and brace plate means interposed between the inner plates and welded thereto and to the bumper plate, the cover plates and side plates extending beyond the inner plates to form a common transverse recess opening downward and rearward for the reception of the upper ends of compression members.

16. A bumper post having a bumper head including a bumper plate and rolled steel plates welded thereto, rolled steel compression members extending downward, outward and rearward from the bumper head and receiving stress of impact therefrom, compression track fixtures each built up by welding from rolled steel plate elements to sustain a plate member in a plane at right angles to the axis of the adjacent compression member which abuts endwise thereon and is welded thereto, and tension structure connecting the bumper head to the road bed in advance of the bumper head.

17. In a bumper post, a bumper head, a pair of H beams having their upper ends fast thereto and extending downward, outward and rearward therefrom, compression track fixtures located opposite each other in the track and having incorporated therein by welding a rail engaging anchor plate and an angle one of whose legs extends downward and rearward toward the track plane and the other of whose legs provides an end abutment for the adjacent H beam whose lower end is welded thereto, and tension structure connecting the bumper head to the road bed at points adjacent the respective rails.

18. In a bumper post, a bumper head, a pair of compression members extending downward, outward and rearward from the bumper head and each having its end abutting on and welded to the leg of an angle, the other leg of which extends downward and rearward therefrom and is welded to a rail engagement plate, and tension structure

connecting the bumper head to the road bed.

19. In a bumper post, a bumper head, a pair of compression members extending downward, outward and rearward from the bumper head and each having its end abutting on and welded to the leg of an angle, the other leg of which extends downward and rearward therefrom, has its edge on the side next the rail extending rearward and inward at an acute angle to the plane of the other leg, and is welded along said edge to the upright flange of a rail engagement angle plate and along its end to the base member of said plate, and tension structure connecting the bumper head with the road bed.

20. In a bumper post, a bumper head, a pair of H beams extending downward, outward and rearward from the bumper head and each having its end abutting on and welded to the leg of an angle, the other leg of which extends downward and rearward therefrom substantially in the plane of a flange of the H beam to a rail engagement plate to which it is welded, and tension structure connecting the bumper head to the road bed.

21. In a bumper post, a bumper head, a pair of H beams extending downward, outward and rearward from the bumper head and each having its end abutting on and welded to the leg of an angle, the other leg of which extends downward and rearward therefrom substantially in the plane of a flange of the H beam and is welded to a rail engagement plate, and an upstanding plate fitting into the angle and welded to both legs of the angle and to the base member of the rail engagement plate and having its upper end in line with the web of the H beam, and tension structure connecting the bumper head to the road bed.

22. In a bumper post, a compression track fixture having a rail engagement angle plate having a base adapted to seat on the rail flange and an upright rail attachment flange adapted to be bolted to the rail web, a compression member-supporting angle plate welded to both legs of the rail engagement angle plate, and an upstanding plate welded to both legs of the compression member-supporting angle plate.

23. In a bumper post, a compression track fixture having a rail engaging anchor plate having a base and an upright rail attachment flange drilled for bolts, a compression member end-abutment welded to the anchor plate and supported above the base plate, and a brace member welded to said plate and abutment.

24. A bumper post having a bumper head, compression means for transmitting thrust of impact therefrom to the road bed, a cross beam seating beneath both the rails, tension track plates each bolted to the web of the adjacent rail on the inside of the rail at

points opposite each other in the track and extending inward therefrom and held fast to the cross beam, and tension members extending downward, outward and forward from the bumper head and each secured to its respective tension track plate between the points of anchorage of the latter to the rail and beam.

25. In a bumper post, a compression track fixture having a plate adapted for attachment to a rail, an angle one of whose legs is supported in a plane at an angle to the horizontal and to the vertical and the other of which extends downward and rearward 10 therefrom and corners on and is welded to said rail attachment plate.

26. A bumper post comprising a bumper head, compression members extending downward, rearward and outward therefrom, and 20 compression track fixtures secured to the compression members and to the respective rails at points opposite each other in the track and each having an upstanding plate member welded thereto provided with a 25 notch having an upper open end adapted to receive the bar of a cross tie bar and having a lug welded thereto in position to overhang the head of the cross bar when the parts are in completely assembled position to prevent 30 the removal of the tie bar.

27. In a bumper post, a tension bar having its ends extended through plates located in different planes and welded to the bar, one of said plates having means for attachment 35 to the head and the other having means for securing it to the rail.

28. In a bumper post, an offsetting block having a hole therethrough having its walls normal to a face of the block, a tension bar 40 passing through said hole at an angle to its axis so as to touch opposite parts of the edge of the hole at the upper and under sides respectively and leave room in the hole at both sides of the plate for welding material.

45. 29. A bumper post comprising a bumper head, compression members supporting the same from the road bed, tension bars passing through offsetting blocks and welded thereto, said bumper having a top plate provided 50 at each side with a groove adapted to receive the adjacent tension bar, a bottom plate, each offset block, each compression member and the top and bottom plates of the bumper head being drilled to receive a connecting bolt, and

55 a connecting bolt for each tension bar connecting structure securing the parts together.

30. In a bumper post, a tension member adapted to be secured at one end to the bumper head and extending downward, forward and outward therefrom and passing through a hole in and welded to a tension track fixture, and means for securing said track fixture to the road bed.

31. A bumper post comprising a bumper 60 head, means for transmitting stress of impact

therefrom as compression to the road bed, and tension members extending downward, outward and forward from the bumper head to points adjacent the rails and there passing through holes in tension track fixtures and welded thereto, and a tension cross beam seating under the respective track rails, said track fixtures being provided with means for securing them respectively to the adjacent rail at the inside of the rail, and with means for exerting pull on the tension cross beam.

32. In a bumper post, a bumper head, means for transmitting thrust of impact therefrom to the road bed, tension track connections from the bumper head to the road bed each comprising a tension track fixture plate bolted to the web of the rail at the inside of the rail and extending substantially horizontally in a plane between the rail head and rail flange, a tension cross beam seating under both rails, and means for delivering stress of impact from the bumper head to said tension track fixture plates and through them to the cross beam.

33. A bumper post comprising a bumper head, tension track fixtures secured to the respective rails at points opposite to each other in the track, a tension cross beam extending across the track seating beneath both rails, said track fixtures having spacer blocks on the top of the cross beam and tension members extending downward, outward and forward from the bumper head to and through holes in said tension track fixtures to which their lower ends are respectively welded, said fixtures being held fast to the cross beam to deliver stress of bumper impact thereto.

34. A bumper post comprising a bumper head, compression means for transmitting thrust of impact therefrom to the road bed, tension members secured to the bumper head and extending outward, downward and forward therefrom to the road bed, tension track fixtures located opposite each other in the track, a cross beam extending across the track at the location of the tension track fixtures and seating beneath both rails, means connecting said respective track fixtures and beam, said tension members extending through holes in said track fixtures between their points of attachment to the rail and the beam respectively and welded to said track fixture plates at both sides thereof.

35. In a bumper post, a bumper head, compression means for delivering thrust of impact therefrom to the road bed, composite tension structure comprising a cross beam extending across the track and adapted to seat beneath both rails, tension track fixture plates secured at the inside of the respective rails at points opposite each other in the track to the respective rail webs and upstanding extensions welded respectively to the front and back of said cross beam and passing through and secured to the adjacent tension track fix-

ture plate, and tension members secured to the bumper head and extending downward, forward and outward to said plates and through holes therein and welded thereto.

36. In a bumper post, a bumper head, compression means for delivering thrust of impact therefrom to the roadbed, composite tension structure comprising a cross beam extending across the track and adapted to seat beneath both rails, tension track fixtures at points opposite each other in the track, each said tension track fixture and the cross beam having means welded to one of said members for securing them together, and tension members extending from the bumper head to said respective fixtures and secured thereto.

37. A bumper comprising a bumper head, compression means for transmitting thrust of impact therefrom to the road bed, a longitudinal I-beam underlying each rail, a tension cross beam adapted to seat under the inner flange of each I-beam and having welded to the upper side thereof an upstanding lug having its upper side angled to correspond with the angle of the underside of said flange against which it seats, tension track fixtures located opposite each other in the track bolted to the webs of respective rails, means for securing the tension track fixtures to the tension cross beam, and tension members secured to the bumper head and extending downward, outward and forward therefrom to the respective tension track fixtures and there secured to the same, the I-beam lugs facing the respective adjacent tension track fixtures at the inside and acting as stops against their inward movement.

38. A bumper post having a bumper head, compression means for delivering thrust of impact to the road bed, and structure for transmitting tension from the bumper head to the track comprising a metal beam extending across the track and seating under the respective rails, tension track fixtures secured to the rails and each having a loop embracing the beam, and tension members extending downward, outward and forward from the bumper head to said tension track fixture and welded thereto at a point between the connection of the fixture to the rail and its connection to the beam.

39. A bumper post having a bumper head, compression means for delivering thrust of impact to the road bed, and structure for transmitting tension from the bumper head to the track comprising a metal beam extending across the track and seating under the respective rails, a pair of tension plates each having a flange adapted to be bolted to the inside of the web of the rail and having secured to it a loop embracing the beam, and tension members each extending downward, outward and forward from the bump-

er head through a hole in the adjacent tension plate and welded to the plate.

40. A bumper post having a bumper head, compression means for delivering thrust of impact to the road bed, and structure for transmitting tension from the bumper head to the track comprising a metal beam extending across the track and seating under the respective rails, a pair of tension track fixture plates each secured to the rail, means connecting the beam and each said plate, and tension members extending downward, outward and forward from the bumper head to said plates and welded thereto.

41. In a bumper post, a bumper head having a bumper plate bent in horizontal planes on a curve to present a forwardly facing concave surface and supported from the head and spaced forward therefrom to center the coupler.

42. In a bumper post, a bumper head having welded thereto spaced forwardly extending plates having concave front edges and a horizontally concave bumper plate which seats against said concave front edges and is welded to said forwardly extended plates.

43. A bumper post having a bumper head between the rails, strut means secured thereto and to the road bed for transmitting thrust of impact from the bumper head, and divergent tension members secured to the bumper head and each having a side extension for securing the tension member to the adjacent rail and to which a bar portion of the tension member passing through a hole therein is welded, said side extensions being secured to the respective rails at points opposite each other in the track.

44. A bumper post having a bumper head, compression means for transmitting stress of impact therefrom to the road bed, tension structure for transmitting stress of impact to the road bed in advance of the bumper head including a cross beam in substantially the plane of the track seating under both rails, and tension members extending downward, outward and forward from the bumper head through a hole in the tension structure and welded thereto.

45. A bumper post having a bumper head between the rails, compression base structure from which the bumper head is supported, compression members extending downward, outward and rearward from the bumper head, means extending each compression member to the base structure and welded both to the compression member and to the base structure, and tension structure for delivering stress of impact to the road bed.

46. A bumper post having a bumper head, strut means extending downward and rearward therefrom, an angle plate welded to the lower end of the strut means and sup-

ported by the road bed, and tension means for transmitting stress of impact to the road bed.

47. A bumper post comprising a bumper plate, brace plates welded to the back of the bumper plate, strut means associated with said brace plates and bumper plate, fast at the upper end thereto and extending rearward and downward therefrom to the road bed to deliver thereto stress of impact from the bumper plate, and tension bars secured to the bumper head and extending therefrom to the road bed at points opposite each other in the track.

15 48. In a bumper post, bumper head structure including a bumper plate, square-sheared plate pieces cornering on the back of the bumper plate and welded thereto along the line of corner contact, and some of which 20 are welded to each other, said structure having associated therewith and fast thereto the adjacent upper ends of compression members.

49. A bumper post having a bumper head 25 structure comprising a bumper plate and a pair of upstanding brace plates welded to the back of the bumper plate at each side thereof, and H-beams arranged flange side up and having their adjacent upper ends fast to said 30 plate structure and diverging rearward and downward therefrom to the road bed, and tension members connecting the bumper head structure to the road bed adjacent the respective rails at points opposite each other 35 in the track.

In testimony whereof, I have signed this specification.

STANLEY W. HAYES.
